(57) **CLAIM**

I claim the ornamental design for a shoe protector, as shown and described.

DESCRIPTION

FIG. 1 is a top, front, left side perspective view of the shoe protector shown in use on a shoe;

FIG. 2 is a top, front, right side view thereof;

FIG. 3 is a top, front, left side perspective view of the shoe protector of FIG. 1 shown without the shoe environment;

FIG. 4 is a front elevation view thereof;

FIG. 5 is a rear elevation view thereof;

FIG. 6 is a left-side elevation view thereof, shown at a reduced scale;

FIG. 7 is a right-side elevation view thereof, shown at a reduced scale;

FIG. 8 is a top plan view thereof; and,

FIG. 9 is a bottom plan view thereof.

The broken lines in FIGS. 1 and 2 show a shoe environment that forms no part of the claimed design.
